UNITED STATES PATENT OFFICE.

ROBERT H. HENEMIER, OF NEW YORK, N. Y.

HORSESHOE PAD.

1,402,768.

Specification of Letters Patent. Patented Jan. 10, 1922.

Application filed May 5, 1920. Serial No. 379,019.

To all whom it may concern:

Be it known that I, ROBERT H. HENEMIER, a citizen of the United States, and residing at New York, in the county of New York and State of New York, have invented certain new and useful Improvements in Horseshoe Pads, of which the following is a specification, such as will enable those skilled in the art to which it appertains to make and use the same.

This invention relates to what are known as horseshoe pads and principally devices of this class composed of resilient material, such for example as rubber, or rubber and canvas; and the object of this invention is to provide a device of the class specified with a detachable non-slipping plate which, in addition to its non-slipping feature, also serves to reinforce and strengthen that portion of the pad with which it is connected thus materially extending the life of such pad; a further object being to provide means which is imbedded in the horseshoe pad for detachably connecting the non-slipping plate therewith, said means also serving to reinforce and strengthen that portion of the pad in which it is mounted; and with these and other objects in view the invention consists in a device of the class and for the purpose specified which is simple in construction and operation and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Figure 1 is a bottom plan view of a horseshoe pad of the usual form and construction, and showing my improvement mounted in connection therewith;

Fig. 2 is a view similar to Fig. 1 but showing only a part of the construction with parts omitted and with part of the construction broken away and in section;

Fig. 3 is a partial section on the line 3—3 of Fig. 1 and on an enlarged scale; and

Fig. 4 is a partial section on the line 4—4 of Fig. 1 on an enlarged scale and showing a slight modification.

In Figs. 1 to 3 inclusive, I have shown at 5 a horseshoe pad constructed in the usual or any desired manner and which, in the construction shown, consists of an approxi-

mately disk-shaped portion 6 composed of rubber, or similar resilient material having a fibrous or rubber and fibrous facing 7. The heel portion 8 of the pad is provided on one face thereof with a projecting portion 9 which extends transversely of the pad and the rear end of which is slightly arc-shaped in form as shown at 10 and the free end of which is provided with forwardly directed rib portions 11.

The horseshoe pad, as above described, is commonly known upon the present market, and is shown to illustrate one use of my invention, it being understood that any desired form of pad may be employed for carrying my invention into effect. In practice, I imbed in the projecting portion 9 of the pad 5 an anchor and reinforcing member 12 which, in the form of construction shown, consists of a strip of metal 13 having an enlarged base 14, and at the end portions thereof are approximately circular bosses 15, preferably formed integrally with the strip 13. The bosses 15 are provided with enlarged heads 16, the periphery of which is cut out at intervals as shown at 17 to permit the material of the projecting portion 9 to firmly secure the bosses 15 or the heads 16 thereof in position. The strip 13 is provided with a plurality of apertures 18 through which the material of the projecting portion 9 passes to aid in holding and securing the member 12 in position.

The member 12 is imbedded in the projection 9 of the pad intermediate of the top and bottom faces of the pad or said projection, as clearly shown in Figs. 3 and 4, so that the resilient action of the projection 9 will not be materially affected, and the projection 9 is provided with apertures 19 which open outwardly through that portion of said projection in which the bosses 15 are located.

The outer face of the projection 9 is provided with a recess 20 adapted to receive a plate member 21 which conforms with the shape of said recess, and the outer face of the plate member 21 is fashioned into a plurality of projecting members 22 to form a gripping surface on said plate member; and screws, bolts, or similar devices 23 are passed inwardly through the plate member and into threaded apertures 24 in the bosses 15, as is clearly illustrated in Figs. 3 and 4 of the drawing. It will be noted that the projecting members 22 of the plate member 21

extend beyond the outer face of the projection 9 of the pad and serve to take up the wear and also present a good non-slipping surface for such pad; and when the plate member 21 becomes worn, a new plate member may be substituted therefor, and in this way the life of the horseshoe pad will be materially prolonged, as there will be little or no wear upon said pad or the projection 9 thereof. It will also be understood that in the use of the device with the plate member 21 secured thereto, the resilient qualities of the pad, or of the projection 9 to which the plate member 21 is secured and in which the anchor or reinforcing member is mounted, will be retained. The member 12 in addition to serving as means for attaching the plate member to the pad also serves to reinforce and strengthen the projection 9 of such pad. It will also be seen that by mounting the plate member 21 in connection with the member 12 in the manner shown in Fig. 3, the plate member 21 is capable of inward movement on the bolt devices 23 to a slight extent and is cushioned in this movement.

In Fig. 4 of the drawing I have shown a slight modification of the construction shown in Figs. 1 to 3 inclusive, in which the bosses 15 of the member 12 are provided with forwardly directed rib members 25, which extend into the ribs 11 of the pad 5 and serve to reinforce said ribs, and the rib members 25 are also preferably provided with apertures 26 through which the material of the ribs 11 is adapted to pass to securely hold and bind the rib members 25 in position.

It will be apparent that the member 12 constructed as shown in Figs. 1 to 3 inclusive, or as shown in Fig. 4, is preferably imbedded in the pad in the manufacture of said pad and forms a part of the pad when produced. The plate members 21 may be connected with the pad whenever desired and new plate members substituted for old and worn-out ones whenever necessary. While I have shown a horseshoe pad of specific form and construction, it will be apparent that my invention is adapted for use in connection with any kind or class of pad, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A horseshoe pad of the class described comprising a substantially disk-shaped base having on one face thereof a projecting portion provided with forwardly directed ribs, said base, projecting portion, and ribs being composed of resilient material, an anchor member imbedded in the projecting

portion of said pad and adapted to reinforce the same, said anchor member comprising a metallic strip at the ends of which are bosses which open outwardly through the outer face of the projecting portion of the pad, 70 said face of the projecting portion being provided with a recess, a plate member mounted in said recess, and means passed through said plate member and into the bosses of the anchor member for securely holding said plate member in position.

2. A horseshoe pad of the class described comprising a substantially disk-shaped base having on one face thereof a projecting portion provided with forwardly directed ribs, 80 said base, projecting portion, and ribs being composed of resilient material, an anchor member imbedded in the projecting portion of said pad and adapted to reinforce the same, said anchor member comprising a metallic strip at the ends of which are bosses which open outwardly through the outer face of the projecting portion of the pad, 85 said face of the projecting portion being provided with a recess, a plate member mounted in said recess, means passed through said plate member and into the bosses of the anchor member for securely holding said plate member in position, and said anchor member being provided with rib members which project into the ribs of said pad and serve to reinforce the same.

3. In a horseshoe pad of the class described, a plate member forming a facing for a portion of a pad, and means imbedded in 100 said pad whereby said plate member may be detachably connected with said pad when the pad is in use.

4. In a horseshoe pad of the class described provided with an enlarged portion, a 105 non-slipping plate member adapted to be mounted in the face of said enlarged portion, an anchor member imbedded in the enlarged portion of the pad and adapted to reinforce the same, and means for detachably connecting said non-slipping plate member with said anchor member in such manner as to form a cushion mounting and support for said plate member.

5. A horseshoe pad of the class described comprising a substantially disk-shaped base having on one face thereof a projecting portion, said base and projecting portion being composed of resilient material, an anchor member imbedded in the projecting portion 110 of said pad and adapted to reinforce the same, the outer face of the projecting portion of the pad being provided with a recess, a non-slipping plate member mounted in said recess and forming a facing for said projecting portion, and means for securing said plate member to said anchor member in such manner as to form a resilient backing for said plate member.

6. In a horseshoe pad of the class de- 130

scribed, an anchor and reinforcing member imbedded in a portion of said pad, a plate member forming a facing for said pad, and means passed through said plate member, 5 said pad, and said anchor and reinforcing member for securing said plate member to said pad in such manner as to form a resilient backing therefor.

7. In a horseshoe pad of the class de-
scribed provided with an enlarged portion, 10 an anchor and reinforcing member imbedded in said enlarged portion of the pad, a plate member mounted in a recess in the face of said enlarged portion, and means for de-
tachably securing said plate member to said 15 anchor and reinforcing member.

8. In a horseshoe pad of the class de-
scribed provided with an enlarged portion, a 20 plate member imbedded horizontally in the face of said enlarged portion, and means in said enlarged portion of the pad with which said plate member is detachably con-
nected.

In testimony that I claim the foregoing as my invention I have signed my name in 25 presence of the subscribing witnesses this 3rd day of May, 1920.

ROBERT H. HENEMIER.
